UNITED STATES PATENT OFFICE.

CARL M. CARLSON, OF OWATONNA, MINNESOTA.

INDICATOR FOR ROTARY CHURNS.

1,086,438.

Specification of Letters Patent.

Patented Feb. 10, 1914.

Application filed August 28, 1912. Serial No. 717,447.

To all whom it may concern:

Be it known that I, CARL M. CARLSON, a citizen of the United States, residing at Owatonna, in the county of Steele and State 5 of Minnesota, have invented certain new and useful Improvements in Indicators for Rotary Churns; and I do hereby declare the following to be a full, clear, and exact description of the invention, such as will enable others skilled in the art to which it 10 appertains to make and use the same.

My invention has for its object to provide an improved indicator, especially adapted for use on rotary churning for sounding an alarm to remind the attendant that a pre-determined number of revolutions of the said churn have been completed; and to this end, the invention consists of the 15 novel devices and combinations of devices 20 hereinafter described in the claims.

The invention is illustrated in the accompanying drawings, wherein like characters indicate like parts throughout the several views.

25 Referring to the drawings, Figure 1 is a view in side elevation of a rotary churn, having applied thereto the improved indicator, some parts of the churn being broken away and some of the exposed parts being shown 30 in section; Fig. 2 is a front view of the improved indicator, on an enlarged scale, some parts thereof being broken away and some of the exposed parts being shown in section; and Fig. 3 is a view principally in edge elevation but with some parts shown in vertical section, taken on the irregular line x^3 of x^3 of Fig. 2.

35 Of the parts of the rotary churn shown, for the purpose of illustrating the improved 40 indicator in working position, the numeral 1 indicates one end of a horizontally extended drum, having secured to the head thereof a trunnion 2, journaled in one end of a suitable supporting frame 3.

45 The parts thus far described may be of the standard or of any desired make, and the drum 1 may be driven by any suitable means, not shown.

50 Referring to my improved indicator, the 55 numeral 4 indicates an annular head or base plate secured, by screws or otherwise, to the outer face of the head of the drum 1 at a point eccentric to the trunnion 2. This base plate 4 is provided, at its axis, with a horizontally extended trunnion 5, having journaled thereon, for a limited swinging move-

ment, a pendulum 6. A pair of circumferentially spaced stop lugs 7 and 8, between which a pendulum 6 swings, are cast integral with the base plate 4, and serve to 60 limit the swinging movement of the pendulum 6. Also journaled on the trunnion 5 outward of the pendulum 6 is an indicator wheel 9. This wheel 9 and the pendulum 6 are held against lateral movement on the 65 trunnion 5 by a machine screw 10, having screw threaded engagement with the trunnion 5, and a co-operating washer 11.

70 On the back of the indicator wheel 9 and at the outer edge thereof are cut or otherwise formed ratchet teeth 12 in annular arrangement, and each one of which represents one revolution of the drum, as will presently appear. The number of ratchet teeth 12 is indicated by numerals, stamped 75 or otherwise marked on the outer face of the indicator wheel 9 and directly opposite the ratchet teeth 12. As shown, these numerals run from 0 to 75, and indicate every fifth ratchet tooth.

80 The indicator wheel 9 is given a step by step movement in the direction of the arrow marked thereon, in Fig. 2, by a driving dog 14, pivotally secured to and between a pair of lugs 15, cast integral with the pendulum 85 6. This driving dog 14 is yieldingly held in engagement with and for action on the ratchet teeth 12 by a small coiled spring 16, compressed between the pendulum 6 and the indicator wheel 9.

90 Co-operating with the ratchet wheel 12, to prevent accidental backward movement of the indicator wheel 9, is a spring pressed retaining dog 17, pivotally secured to a lug 18, cast integral with the bearing plate 4. 95

An alarm device, arranged to be actuated at the completion of a certain pre-determined number of revolutions of the drum 1, is secured to the pendulum 6. As shown, this alarm device is preferably in the form of a 100 spring actuated bell, indicated as an entirety by the numeral 19, and of the type commonly known as a bicycle bell. For the purpose of this case, it is not thought necessary to fully illustrate said bell, but it may be 105 here stated that its actuating spring, not shown, is set under tension by rotating the top of the bell with respect to its fixed or base portion. This actuating spring is set in motion by a plunger 20, carried by the 110 base or fixed portion of the bell. Secured to the indicator wheel 9 and located at the

zero point of the numerals marked thereon is a bell actuating device in the form of a can head 21, arranged to travel over the free or outer end of the plunger 20, at the end of the pre-determined number of revolutions of the drum 1, and thereby depress the plunger 20 to release the bell actuating spring. The cam head 21 is provided with a slotted arm 22, through which projects 13 a nut-equipped stud bolt 23, rigidly secured to the outer face of the indicator wheel 9, and projecting laterally therefrom. Obviously, by means of the slotted arm 22, and the nut-equipped stud 23, the cam head 21 15 may be adjusted either toward or from the axis of the indicator wheel 9 or slightly circumferentially, with respect thereto, for the purpose of varying the length of time it is desired to ring the bell 19. For holding the 20 pendulum 6 against swinging movement and in close engagement with the stop lug 7, a swinging arm 24 is pivotally secured at 25 to the base plate 4. At its free end, this arm 24 is provided with a laterally projecting 25 cam extension 26 adapted to be moved into engagement with one of the lateral end extensions of the pendulum 6.

The operation of the improved device may be briefly stated as follows: The indicator 30 wheel 9 is first set in a position corresponding to the number of revolutions it is desired to give the churn; for instance, if it is desired to give the churn thirty-five revolutions, the indicator wheel 9 is turned to a 35 position to bring the ratchet tooth 12, which is directly back of the numeral 35, into engagement with the driving dog 14. The driving means for the drum 1 is then set in motion. Obviously, during each revolution 40 of the drum 1, the pendulum 6 carried thereby will make one complete rotation around the drum trunnion 2. During this rotation of the pendulum 6, the same will also have, under the action of gravity, a limited swinging movement on its pivotal support 5, with respect to the drum 1. In the drawings, the pendulum 6 is shown at its highest point of travel, as the same is moved around the drum trunnion 2, and in engagement with 45 the stop lug 7. As the pendulum 6 is carried downward from this point by the drum 1, the same will, under the action of gravity, drop at a faster speed than the travel of the drum 1, until it is stopped by the lug 8. 50 During this movement of the pendulum 6, the driving dog 14 carried by said pendulum will slip over one of the ratchet teeth 12, and the indicator wheel 9 is held against movement therewith by the retaining dog 17. 55 The pendulum 6 continues in engagement with the stop lug 8 until the same reaches its lowest point of travel as it is moved around the drum trunnion 2. As the pendulum 6 is carried upward from this point 60 by the drum 1, said pendulum, under the

action of gravity, will drop back in respect to the travel of the drum 1, out of engagement with the lug 8 and into engagement with the lug 7. During this backward movement of the pendulum 6, the indicator wheel 9 will also be moved therewith by the driving dog 14, thus moving the cam head 21 one step nearer the bell actuating plunger 20. As the indicator wheel 12 is advanced by the driving dog 14, its ratchet teeth will 70 slip over the retaining dog 17. After the drum 1 has made within about two of the required number of revolutions, the cam head 21 will engage the plunger 20 and, as the drum 1 continues to rotate, the said 75 plunger 21 will be completely depressed, thereby actuating the bell 19, to notify the attendant that the drum 1 has made the required number of revolutions.

The above described device, while extremely simple and of comparatively small cost to manufacture, has, in actual usage, been found highly efficient for the purpose had in view.

What I claim is:

1. The combination with a rotary body, of a pendulum carried by said body, an alarm device carried by said pendulum, an indicator actuated by said pendulum, and means carried by said indicator for actuating said alarm device, at the end of a pre-determined number of revolutions of said body.

2. The combination with a rotary drum, of a pendulum carried by said drum, an alarm device carried by said pendulum, an indicator actuated by said pendulum, and adjustable means carried by said indicator for actuating said alarm device, at the end of a pre-determined number of revolutions of said drum.

3. The combination with a rotary drum, of a pendulum and an indicator wheel carried by said drum, ratchet teeth on said indicator wheel, a driving dog carried by said pendulum, and operative on said ratchet teeth, to impart a step by step movement to said indicator wheel, a retaining dog carried by said drum, and operative on said ratchet teeth, and an alarm device carried by said pendulum, and means carried by said indicator wheel for actuating said alarm device, at the end of a pre-determined number of revolutions of said drum.

4. The combination with a rotary drum, of a trunnion on said drum, a pendulum and an indicator wheel journaled on said trunnion, stops for limiting the swinging movement of said pendulum, a driving dog carried by said pendulum, and operative on said ratchet teeth to impart a step by step movement to said indicator wheel, a retaining dog, carried by said drum, and operative on said ratchet teeth, a bell carried by said pendulum, and a cam head carried by said indicator wheel for actuating said bell, at 125 130

the end of a pre-determined number of revolutions of said drum.

5. The combination with a rotary drum, of a trunnion on said drum, a pendulum and an indicator wheel journaled on said trunnion, stops for limiting the swinging movement of said pendulum, a driving dog carried by said pendulum, and operative on said ratchet teeth to impart a step by step 10 movement to said indicator wheel, a retaining dog, carried by said drum, and operative on said ratchet teeth, a spring actuated plunger-equipped bell, carried by said pendulum, an adjustable cam head carried by 15 said indicator wheel and arranged to depress said plunger, at the end of a pre-determined number of revolutions of said drum for actuating said bell.

6. The combination with a rotary drum, 20 of a trunnion on said drum, a pendulum and an indicator wheel journaled on said

trunnion, stops for limiting the swinging movement of said pendulum, a driving dog carried by said pendulum, and operative on said ratchet teeth to impart a step by step 25 movement to said indicator wheel, a retaining dog, carried by said drum, and operative on said ratchet teeth, a spring actuated plunger-equipped bell, carried by said pendulum, an adjustable cam head carried by 30 said indicator wheel and arranged to depress said plunger, at the end of a pre-determined number of revolutions of said drum for actuating said bell, and means for locking said pendulum against swinging 35 movement.

In testimony whereof I affix my signature in presence of two witnesses.

CARL M. CARLSON.
